FRANK R. McBERTY, OF NEW ROCHELLE, NEW YORK, ASSIGNOR TO WESTERN ELECTRIC COMPANY, OF CHICAGO, ILLINOIS, A CORPORATION OF ILLINOIS.

WIRING SYSTEM FOR TELEPHONE-EXCHANGES.

1,104,062.

Specification of Letters Patent.

Patented July 21, 1914.

Application filed July 24, 1909, Serial No. 509,437. Renewed May 11, 1914. Serial No. 837,925.

To all whom it may concern:

Be it known that I, FRANK R. McBERTY, citizen of the United States, residing at New Rochelle, in the county of Westchester and State of New York, have invented a certain new and useful Improvement in Wiring Systems for Telephone-Exchanges, of which the following is in full, clear, concise, and exact description.

10 My invention relates to the wiring of selectors such as those used in automatic telephone exchange systems, and has for its object to provide an improved arrangement of the conductors whereby less labor is involved 15 in the wiring and a neater and less costly construction is secured than in systems heretofore used.

A well known type of selector for automatic telephone exchange systems is one in which brushes, forming either directly or through suitable mechanism the terminals of a telephone line, are adapted to be moved about a vertical axis and to traverse curved rows of fixed line or trunk terminals. By 25 such selectors, suitable means being provided for moving the brushes, any telephone line of the system may be connected to any other telephone line for telephonic communication.

30 Heretofore groups of selectors of the type referred to have been mounted in horizontal rows, and the corresponding terminals thereof have been connected in multiple by individual wires running substantially parallel to the planes of movement of the brushes. The result of this method of wiring is that the individual wires form a confused and disorderly mass of conductors. Furthermore, the cost of wiring is high on 35 account of the necessity of handling each wire separately, and there is great liability of trouble due to broken connections in the loosely strung wires and at the terminals to which the wires are soldered. On account of 40 the curvature of the rows of terminals cables are not easily adapted to the wiring of horizontal rows of this type of selector.

According to my invention rows of selector switches each having terminals arranged in a cylindrical bank are wired in multiple by cable conductors extending transversely to the curvature of the cylindrical bank and thus transversely to the

planes of movement of the movable terminals or brushes. Preferably the cables lie between adjacent straight rows of terminals, and the conductors of these cables are preferably arranged in ribbon form and folded between said rows on the outer surface of the terminal frame.

I also find it desirable in practice to provide in alignment with and preferably at one end of each row of selectors a connecting rack having terminals arranged in rows corresponding to those of a selector. I extend the cable conductors to make connection with the terminals of the connecting rack, the conductors of each cable being connected to corresponding terminals of the successive rows on the connecting rack just as they are at the selectors. I then provide other cables forming extensions of the telephone lines and connect the conductors of each of these cables with successive terminals in a row on the connecting rack.

It is often necessary in practice to group for one set of telephone lines more selectors than can be conveniently placed in a single row, and my invention is readily adaptable to the requirements of such large groups of selectors. I divide the selectors of a given group into several rows placed side by side and unite in multiple the corresponding terminals of the connecting racks for the several rows of selectors by means of the last mentioned cables. I prefer to arrange my selectors in vertical rows or tiers and the brushes are accordingly mounted to move about vertical axes. This arrangement permits the mounting and wiring of the rows of selectors on vertical sections of a suitable frame and such sectional units may be readily added from time to time to an existing telephone exchange to take care of the increasing traffic by placing them and connecting them up beside and in line with other units already in service.

My invention has special utility in the wiring of selectors in which the terminals thereof are arranged in curved rows. This is due to the fact that the terminals of the successive rows to which my vertical cables are wired lie in straight rows. I am thus enabled to employ flat ribbon cables which are readily formed into shape in the factory and there connected in place by soldering to

the proper terminals. The only wiring necessary in the telephone exchange is accomplished by an orderly arrangement of cables, the conductors of which represent lines of consecutive numbers.

It will be understood that the terminals of selectors are ordinarily numbered successively along the lines of travel of the brushes, this being desirable for obvious reasons, and particularly in large telephone exchanges where many subscribers have a plurality of lines to which consecutive numbers are assigned, and where the brushes of the selectors are adapted in traversing the terminals in succession to pick out and make connection with the first non-busy line. The several conductors in each vertical cable of my system of cabling, therefore, will ordinarily represent lines which do not have consecutive numbers, but on my connecting rack the terminals are numbered consecutively along horizontal rows, and the line connecting cables contain conductors which as I have stated represent lines of consecutive numbers.

I will describe my invention more particularly by reference to the accompanying drawing which shows diagrammatically and in isometric view, an arrangement of apparatus and wiring embodying my invention. I consider it unnecessary and therefore do not show in the drawing a complete telephone exchange system, because such systems are well known in the art, but merely represent the parts thereof to which my invention particularly relates.

In the drawing, *a*, *b*, *c* and *d* represent a group of selectors arranged in two vertical rows or tiers of two selectors each, *a* and *b* constituting one tier and *c* and *d* another. Connecting racks *e* and *f*, one for each tier, are placed in vertical alinement with the selectors. Each selector may comprise, as I have shown, ten horizontal rows of ten terminals each, and ten brushes *g*, one for each row of terminals. These terminals are fixed in cylindrical frames *h* and the inner ends of the terminals form curved rows traversed by the brushes as they move about the spindles *i*. The connecting racks are likewise provided with terminals corresponding to those of a selector; there being, as I have shown in the drawing, ten horizontal rows of ten terminals each on each rack.

The terminals on the selectors and on the connecting rack may represent lines to which consecutive numbers are assigned, and I have in the drawing numbered the terminals of each selector and connecting rack of the group from 0 to 99, beginning at the top row and at the right and progressing to the left along successive rows.

In each row of selectors the terminals are wired by cables *k* running vertically, and therefore, at right angles to the planes of

movement of the brushes. The conductors of each of these cables unite terminals of the successive rows of one of the selectors with the corresponding terminals of the other selectors and connecting rack in line therewith. These cables are represented in the drawing by groups of wires, and two cables for each tier of selectors are shown, it being understood that there would be as many such cables for each tier as there are terminals in a horizontal row on a selector. Each cable is preferably constructed with its wires arranged side by side in a flat ribbon, said ribbon being folded as shown to bring the individual wires into proper position to be soldered direct to the selector terminals. The system of cabling herein described makes possible such direct connection of the wires to the terminals without requiring "fanning out" wires. It will be noted that the conductors of cable *k*, farthest to the left in the drawing, are connected respectively to those terminals of selectors *a* and *b* and connecting rack *e* which are numbered 9, 19, etc., to 99, while cable *k*, farthest to the right, contains conductors which are connected respectively to the terminals representing lines 0, 10, etc., to 90 of selectors *c* and *d* and connecting rack *f*. The corresponding terminals of the connecting racks are united by the conductors of cables *l*, which preferably run as I have shown them in a horizontal direction. The conductors of each of these last mentioned cables connect successive terminals in a row on one of the connecting racks with the corresponding terminals on the other rack. There may be if desired as many such cables as rows of terminals on a connecting rack and, therefore, ten in the arrangement shown in the drawing. It will be noted that cable *l*, shown uppermost in the drawing, comprises conductors numbered consecutively 0 to 9, inclusive, which are connected respectively to correspondingly numbered terminals of the connecting racks.

It is obvious that more than two selectors may be placed in each tier and the terminals thereof united by extending cables *k*, and that more than two tiers of selectors may be grouped together by extending cables *l* to the connecting racks of the additional tiers. It is also obvious that the selectors may have any desired number of terminals and that these may be in pairs or in triples, as is customary in automatic telephone exchange systems. Any suitable means may be employed for causing the brushes to move about the spindles and to connect them with the desired terminals and any suitable mechanism may be employed for extending the connections from the brushes and from the conductors of cables *l* to the different lines. I have in practice employed selectors having 200 sets of terminals; each set comprising two line terminals and one local terminal.

- 5 minal, these terminals being arranged in ten horizontal curved rows, of twenty sets each. For such selectors I prefer to employ ten sets of brushes, one for each row, moving 5 about a common spindle, although, if it is desired, a single set of brushes may be employed and arranged to be moved vertically opposite the particular row and then horizontally to the terminals of the line desired.
- 10 10 Obviously my system of cabling may be employed in telephone exchange systems varying widely in detail and in general wherever selectors of the type referred to are used.
- 15 15 Having thus described my invention, what I claim is:
1. A row of selectors each having terminals arranged in curved rows and in intersecting straight rows, and brushes arranged 20 to traverse said curved rows, in combination with a cable having conductors uniting terminals of successive rows on one selector with corresponding terminals on the other 25 selectors, said cable running at a right angle to the planes of movement of the brushes and between the straight rows of terminals.
  2. A selector having terminals in curved rows and brushes arranged to traverse said 30 rows, in combination with a connecting rack having rows of terminals corresponding to said rows of the selector, a cable having conductors uniting terminals of the successive rows on the selector with corresponding 35 terminals on the connecting rack, said cable running at a right angle to the planes of movement of said brushes, and a second cable having conductors connected to successive terminals of a row on the connecting 40 rack.
  3. A selector having terminals arranged in curved rows and straight rows, at right angles to said curved rows and brushes adapted to traverse said curved rows, in 45 combination with a connecting rack having terminals arranged in rows corresponding to those of the selector, a plurality of cables, the conductors of each of which unite successive terminals in a straight row on the 50 selector with the corresponding terminals on the connecting rack, said cables running in the direction of said straight rows of terminals, and a plurality of other cables, the conductors of each of which are connected to successive terminals of a row on the connecting 55 rack corresponding to a curved row on the selector.
  4. A row of selectors, each having terminals arranged to form curved rows and 60 straight rows at right angles to said curved rows, and brushes adapted to traverse said curved rows, in combination with a connecting rack in line with the row of selectors having terminals arranged in rows corresponding to those of a selector, a plurality 65 of cables, the conductors of each of which unite successive terminals in a straight row on one selector with the corresponding terminals on the other selector, and a plurality of other cables, the conductors of each of which are connected to successive terminals in a row on the connecting rack corresponding to curved rows on the selector.
  5. A group of selectors, each having curved rows of terminals, and brushes arranged to traverse said rows, said selectors being arranged in rows extending at right angles to the planes of movement of the brushes, in combination with connecting racks, one in line with each row of selectors and having terminals corresponding to those of a selector, conductors running in the direction of said rows of selectors and uniting in multiple the corresponding terminals of the selectors in each row and connecting in line therewith, and other conductors arranged to unite corresponding terminals of the connecting racks.
  6. A plurality of rows of selectors, each selector having terminals arranged to form curved rows and straight rows at right angles to said curved rows, and brushes adapted to traverse said curved rows, said rows of selectors extending at right angles to the planes of movement of the brushes, in combination with a plurality of connecting racks one in line with each row of selectors and having terminals in rows corresponding to those of a selector, a plurality of cables, each having conductors uniting successive terminals in a straight row of one selector with the corresponding terminals of the other selectors and connecting rack in line therewith, and a plurality of other cables, each of which has conductors uniting successive terminals in rows on the connecting racks corresponding to the curved rows on the selector.
  7. A group of selectors arranged in vertical tiers, each selector having horizontal rows of terminals and brushes adapted to traverse said rows, in combination with connecting racks one in line with each tier and having rows of terminals corresponding to those of a selector, a plurality of vertically running cables, each cable having conductors uniting terminals in successive rows of one selector with the corresponding terminals of the other selectors and connecting rack in line therewith, and a plurality of other cables each having conductors uniting successive terminals in corresponding rows of the connecting racks.
  8. A group of selectors, each having horizontal rows of terminals, and brushes adapted to traverse said rows, said selectors being arranged in vertical tiers, in combination with connecting racks one in line with each tier and having rows of terminals corresponding to those of a selector, a plurality of vertically running cables, each cable having conductors uniting terminals in successive rows of one selector with the corresponding terminals of the other selectors and connecting rack in line therewith, and a plurality of other cables each having conductors uniting successive terminals in corresponding rows of the connecting racks.

with connecting racks, one in line with each tier and having horizontal rows of terminals corresponding to those of a selector, a plurality of flat formed cables, each having 5 conductors uniting terminals in successive rows of one selector with the corresponding terminals of the other selectors and connecting rack in line therewith, and a plurality of other cables, each having conductors uniting 10 successive terminals in corresponding rows on the connecting racks.

9. A group of selectors, each having terminals arranged in curved rows about a cylindrical frame, and brushes adapted to rotate about vertical axes along said curved 15 rows, said selectors being arranged in vertical tiers, in combination with connecting racks, one in line with each tier of selectors and having terminals arranged in rows corresponding 20 to those of a selector, a plurality of vertically running cables, each cable having conductors uniting terminals in successive rows of one selector with the corresponding terminals of the other selectors 25 and connecting rack in line therewith, and conductors arranged to unite corresponding terminals of the connecting racks.

10. A group of selectors, each having terminals arranged in curved rows about a cylindrical frame, and brushes adapted to rotate about vertical axes along said curved rows, said selectors being arranged in vertical tiers, in combination with connecting racks, one in line with each tier of selectors 30 and having terminals arranged in rows corresponding to those of a selector, a plurality of vertically running cables, each cable having conductors uniting terminals in successive rows of one selector with the corresponding 35 terminals of the other selectors and connecting rack in line therewith, and a plurality of other cables, each having conductors uniting successive terminals in corresponding rows of the connecting racks.

40 11. A selector having terminals arranged in curved rows and intersecting straight rows, in combination with cables, one for each straight row of terminals, the conductors of each of said cables being connected respectively to successive terminals in one of said straight rows, and other cables, the conductors of each of which are connected respectively to those conductors of the several first mentioned cables which are connected 45 to successive terminals in one of said curved rows.

12. A selector having terminals arranged in curved rows and intersecting straight rows, in combination with ribbon cables, one 50 for each straight row of terminals, the conductors of each of said cables lying parallel to one another and being connected respectively to successive terminals in one of said straight rows, and other cables, the conductors of each of which are connected re-

spectively to those conductors of the said ribbon cables which are connected to successive terminals in one of said curved rows.

13. A row of selectors each having terminals arranged in curved rows and intersecting straight rows, in combination with flat ribbon cables, the conductors of each of said cables being connected respectively to corresponding terminals in said straight rows and other cables, the conductors of each of which are connected respectively to those conductors of said flat ribbon cables which are connected to successive terminals in said curved rows. 70 75

14. A row of selectors each having terminals arranged in curved rows and intersecting straight rows, in combination with flat ribbon cables, each of said cables being folded along diagonal lines and having its conductors respectively connected at alternate folds to corresponding terminals in said straight rows, and other cables, the conductors of each of which are connected respectively to those conductors in said flat ribbon cables which are connected respectively to successive terminals in said curved rows. 80 85 90

15. A selector having terminals arranged in curved rows and straight rows at right angles to said curved rows and brushes adapted to traverse said terminals, in combination with cables, one for each straight row of terminals and running in the direction of said straight rows, the conductors of each of said cables being connected respectively to successive terminals in a straight row on the selector, and other cables, the conductors of each of which are connected respectively to those conductors of the first mentioned cables which are connected respectively to successive terminals in a curved row on the selector. 95 100 110

16. The combination with a group of cables containing wires of consecutively-numbered lines, of a connecting rack having terminals to which said wires are connected, a group of selectors having terminals for said lines, and cables connecting said selector terminals to said connecting rack terminals, each of said last mentioned cables containing wires which are connected at said rack to wires of different cables of the first mentioned group. 115

17. In a switch, the combination with a plurality of selectors arranged in a row, 12 each selector having terminals arranged in curved rows and intersecting straight rows, of means for electrically connecting the corresponding terminals of said selectors in multiple, consisting of a series of cable conductors extending parallel to and between said straight rows. 125

18. In a switch, the combination with a plurality of selectors arranged in a row, each selector having terminals arranged in

1. a cylindrical bank and forming curved and straight rows, of means for electrically connecting the corresponding terminals of the selectors in multiple, consisting of a series 5 of conductors placed between and running parallel to the straight rows of terminals.
2. In a switch, the combination with a plurality of selectors arranged in a row, each selector having terminals arranged in a cylindrical frame, said terminals extending radially from the outer surface of said frame and forming curved and straight rows, of means for electrically connecting the corresponding terminals of said selectors in 10 multiple, consisting of a series of conductors placed between and running parallel to adjacent straight rows of terminals on the outer surface of said frame.
3. In a switch, the combination with a plurality of selectors arranged in a row, each selector having terminals arranged in a cylindrical bank and forming curved and straight rows, of means for electrically connecting the corresponding terminals of said selectors in 15 multiple, consisting of a series of conductors arranged in ribbon form and folded between adjacent straight rows of terminals.
4. In a switch, the combination with a plurality of selectors arranged in a row, each selector having terminals arranged in a cylindrical bank and forming curved and straight rows, of means for electrically connecting the corresponding terminals of said 20 selectors in multiple, consisting of a series of cable conductors arranged in ribbon form and folded between adjacent straight rows of terminals.
5. In a multiple cabling system, the combination with groups of closely spaced terminals arranged in rows, of a cable connecting terminals of said groups in multiple relation, said cable consisting of a ribbon or band of wires lying between adjacent rows 25 of terminals.
6. The combination with a row of ter-

minals having a certain spacing, of a flat cable comprising a layer of wires, having a closer spacing than the terminals, said wires being directly connected with the terminals, 40 by having the cable disposed at such an angle with respect to the row of terminals as to cause each wire of the cable to directly intersect the corresponding terminal.

7. In a multiple cabling system, the combination with groups of terminals arranged in closely spaced rows, of flat cables connecting corresponding rows in each group, said cables lying between the rows of terminals. 45

8. In a multiple cable system, the combination with groups of terminals arranged in closely spaced rows, of flat cables connecting corresponding rows in each group, said cables lying between the rows of terminals, 50 each cable being folded over the associated row in each group to cause the wires of the cable to overlie the ends of the terminals.

9. The combination with a group of terminals arranged in closely spaced rows, of flat cables lying within the spaces between adjacent rows of terminals and having their wires brought out to the edges of the spaces for connection with the ends of said terminals. 55

In witness whereof, I hereunto subscribe my name this 22nd day of July, A. D. 1909.

FRANK R. McBERTY.
